UNITED STATES PATENT OFFICE

112,102

DESIGN FOR A POWER TRANSMITTING UNIT

Leonard J. Bishop, Detroit, Mich., assignor to
Mechanical Handling Systems, Inc., Detroit,
Mich., a corporation of Michigan

Application February 23, 1937, Serial No. 67,814

Term of patent 7 years

To all whom it may concern:

Be it known that I, Leonard J. Bishop, a citizen of the United States of America, residing at Detroit, in the county of Wayne and State of Michigan, have invented a certain new, original, and ornamental Design for a Power Transmitting Unit, of which the following is a specification, reference being had therein to the accompanying drawing forming a part thereof, in which Figure 1 is a front respective view of a power transmitting unit embodying my new design and constituting a unit for driving industrial conveyors and the like; and Figure 2 is a rear perspective view thereof.

The characteristic features of the design reside

in the rectangular outline of the housing having its upper corners rounded and having a base which projects slightly beyond the ends of the housing, the housing having oppositely positioned oblong openings in the sides thereof, one of the openings having a beaded margin and the other having a flanged projection, the housing also having a cap on the top thereof and an extension in one end which terminates in a disk-like member having a handle near the edge thereof, all as shown.

I claim:

The ornamental design for a power transmitting unit, substantially as shown and described.

LEONARD J. BISHOP.
